UNITED STATES PATENT OFFICE

PETER GARMS, OF NEW YORK, AND GEORGE LEWIS DIGGLES, OF FLUSHING, NEW YORK, ASSIGNORS TO ELECTRICAL TESTING LABORATORIES, OF NEW YORK, N. Y., A CORPORATION OF NEW YORK

THERMOSTATIC RADIATION INDICATOR

Application filed January 2, 1932. Serial No. 584,498.

The present invention has for its object to provide an apparatus for use in testing the life of filaments in incandescent electric lamps and accurately recording the length 5 of time such filaments will burn under a given current rating.

In the commercial manufacture of electric lamps, it is desirable to determine from time to time their normal life expectancy. 10 This is ordinarily accomplished by performing life tests against current on samples of the lamps manufactured, and these tests require careful observations as to the periods of time over which the filaments extend until they are disrupted.

The present invention has for an object to provide a device for the testing of electric lamp filaments, which will require minimum attention on the part of the operator in performing the tests and will provide an automatic registration of the elapsed time.

To these and other ends our invention comprises further improvements all as will be more fully described in the following specification, the novel features thereof being particularly pointed out in the appended claims.

In the drawings:

Fig. 1 is a schematic illustration of one embodiment of the invention; Fig. 2 is a plan view of the temperature-controlled switch of Fig. 1, located within a housing, a portion of the cover plate being broken away; Fig. 3 is a cross-sectional view taken on the line 3—3 of Fig. 2, including additional parts not shown in Figs. 1 and 2; Fig. 4 is a fragmentary plan view of the housing cover plate; Fig. 5 is an enlarged fragmentary cross-sectional view taken on the line 5—5 of Fig. 2; Fig. 6 is a schematic illustration of another embodiment of the invention; and Fig. 7 is a view in elevation showing a mechanical assembly of the thermostat in relation to an electric lamp to be tested.

In Fig. 1 we have shown schematically an incandescent electric lamp 1 which is preferably disposed in a vertical position and a temperature-controlled switch 2 comprising an arcuate thermal expansion-strip 3 surrounding a portion of the lamp and disposed 45 in a horizontal position. The radius of cur-

vature of the expansion-strip 3 is such as to accommodate lamps of different size and type. In the embodiment of the invention shown, the expansion-strip 3 surrounds the neck-portion of the lamp, although it is understood that it may surround the body proper. The thermal expansion-strip 3 is preferably of the bimetallic type comprising an outer element 4 made of a metallic material having a relatively low coefficient of expansion, such as the alloy known in the trade as "Invar", and an inner element 5 made of a different metal having a relatively high coefficient of expansion, such as brass. A conducting supporting strip or bar 6 may be secured by rivets 7 to one end of the strip and serve as a support, and at its other extremity or free end another strip 10 may be attached by rivets 9 and serve as a circuit contact member arranged in one side of the circuit of an automatic timing device or time register, such as an electric clock 14. One terminal of the latter is connected by a conductor 12 to the bar 6 by the binding screw 11. The other terminal of the register is connected through a conductor 15 to one side of an electric current source 16, which is preferably the usual alternating current house lighting circuit. A second conductor 17 is connected at one end to the other side of the current source 16 and leads to a co-operating switch contact 21 on a conducting bar 19 to which said conductor is attached by the binding screw 20. The contact 21 is in the form of a set screw having a lock nut 22, and cooperates with the contact 10 in establishing a circuit connection to permit current to flow from the source 16 through the switch 2 and the time register 14 when the strip 3 is expanded, and in interrupting such connection to check the flow of such current when the expansion-strip contracts. The arm 19 is carried by a block 23 of insulating material and is formed at one side with an extension 24 carrying another set screw 25 which forms a back stop also cooperating with the arm 10 in a manner to be presently understood. The block 23 is formed with an aperture 26 through which extends a journal pin 27, whereby the 55 60 65 70 75 80 85 90 95 100

block may turn or rotate slightly in one direction under the influence of the arm 10 bearing against the contact 21, when the thermal-strip is in the act of expanding, and 5 to rotate in the other direction as the arm 10 bears against the stud 25, during the contracting movement of said member. Friction means, to be hereinafter more particularly described, is preferably provided to 10 prevent accidental displacement of the block 23 from its set position as determined by the actuating arm 10.

This construction of the switch 2 with particular reference to the oscillating character 15 of the spaced elements 21 and 25 is an important feature of the invention in that it permits the thermal-strip 3 to expand freely to its fullest extent as determined by the heat radiated by the lamp filament 13 when current is passed therethrough. The amount 20 of expansion of the strip 3 depends on the size or wattage of a particular lamp undergoing test, or the amount of heat radiated, and the switch 2 therefore permits life tests 25 to be performed with accuracy over a wide range of lamps of varying wattage, because a comparatively quick return or contraction of the thermal member strip 3 from its expanded position is assured in each case and 30 very little time elapses before the breaking of the circuit occurs by the separation of contacts 10 and 21, when the heat radiated from the lamp bulb is interrupted by the breakdown or burning out of its filament.

35 The adjacent ends of the set screws 21 and 25 are so adjusted in the first instance that a quick closing of the cooperating contacts 10 and 21 occurs when current is supplied to the lamp filament.

40 To shorten the time required in performing life tests on electric lamp filaments, the latter are tested against an adverse current or over voltage condition, which may be 150% of the normal current or voltage to 45 which such filaments are subjected in service, the normal life of a given filament being computed by an empirical formula applicable to the particular type of lamp undergoing study, using the data obtained in the 50 over-voltage test. In order that the current to be passed through the filament may be derived from the usual house lighting circuit, we provide the apparatus with means for increasing the normal live voltage from 55 such source and our testing apparatus includes means for varying or adjusting the over-voltage applied to a lamp filament to the required value. As shown in Fig. 1, our apparatus comprises a step-up transformer 28 the primary or low-tension winding 29 of which is connected by conductors 30 and 31 to the output terminals of a double pole switch 32, which when closed is connected by conductors 34 and 35 to the terminals of the current source 16. The sec-

ondary or high-tension winding 36 of the transformer has a side portion provided with a suitable number of taps 37. The lamp base or shell contact 39 and the lamp center contact 40 are connected, through the intermediary of an electric lamp socket (not shown), by the conductors 41 and 42, respectfully, to one end of the winding 36 and to the switch arm 44 of a tap switch 45, which arm 44 cooperates with terminals 46 connected to the taps 37. The switch 45 permits the desired tap to be connected in circuit with the lamp filament and the proper voltage to be applied to said filament.

80 From the above description, it becomes apparent that upon the closing of the switch 32, the heat generated by the lighted filament 13 and radiating from the lamp bulb will cause the thermal-strip 3 to expand, by reason of its bimetallic construction, to quickly close the pair of contacts 10 and 21. The lighting of the filament 13, therefore, causes an almost immediate passage of current through the time register or clock 14, causing 85 it to start.

90 In the embodiment of the invention shown in the drawings, the clock 14 is provided with a dial having its larger divisions calibrated in steps of sixty minutes and its smaller divisions in steps of one minute duration, whereby the elapsed time may conveniently be read from the dial directly in minutes. At the beginning of a test the two clock hands are preferably adjusted (prior to the 95 closing of the switch 32) to point to the zero position on the dial, so that thereafter the clock reading is an indication of the actual length or duration of the test.

100 The flow of excess current through the filament 13 will in time cause it to burn out, and almost in immediate response to the interruption of current through the filament there occurs a corresponding inward movement or contraction of the thermal-strip 3, which opens the contacts 10 and 21 to disconnect the clock circuit and interrupt its movement. The hour and minute hands, in their position of arrest, then indicate 105 the actual period of time the lamp filament 13 was in full service. It will be noted that any sluggishness in the expanding and contracting of the thermal member is compensated for in the record made, because whatever time is lost in the closing of the switch contacts 10 and 21, at the start of the test, is offset by the time required to open said contacts when the test is terminated.

110 As shown in Figs. 2 and 3, the temperature-controlled switch 2 and parts associated therewith are preferably mounted with 115 in a housing 47 comprising a recessed bottom member 49 and a cover plate 50 secured thereto by screws 51. These parts 49 and 50 are made of suitable insulating material, such as bakelite, and the bottom member 49

may be made in a single piece molded in the desired shape. The supporting bar 6 is secured, as by the screws 11 and 52, to a side wall of the recess 54, and one of the screws 8 is utilized as a binding post for the conductor 12. The members 49 and 50 are formed with corresponding openings 55 and 56 to permit insertion of the stem or body of a lamp through the interior of the temperature-controlled member 3, and a suitable number of ventilation apertures 57 are circularly disposed in both members 49 and 50 to facilitate the circulation of air into contact with the thermal member 3. 10 The insulating block 23 carrying the pair of stops 21 and 25 is supported freely in the recess 54, as more clearly shown in Fig. 5, on its journal pin 27. The latter is rigidly secured to the bottom member 49 by a screw 20 portion 58 and a nut 59 and above said nut a bearing washer 60 provides a seating surface for the block 23. As loosely fitting cap 61 surrounds the upper end portion of the pin 27 and has a lower flanged end 62 bearing against the block 23. This cap 61 extends through an opening 63 in the cover plate 50, in which opening it is free to move when the block 23 is actuated by the thermal member 3. A flat spring 64 mounted on the cover 50 bears against the upper end of the cap 61 to provide sufficient friction to prevent displacement of the block 23 other than that caused by the expansion or contraction of the member 3. If desired the bearing pressure of the spring may be regulated by a screw 65 which engages a threaded stud 66 carried by the cover plate 50. 30

An opening 69 formed through the side wall of the bottom member 49 accommodates the conductors 12 and 17 leading to the switch 2, the former leading directly to the conducting bar 6, and the latter being connected through a binding post 70 to one end of a "pigtail" or coil wire 17a, the other extremity of which is connected by the binding screw 20 to the bar 19. This coil 17a is made of fine wire to avoid any offsetting torque from being applied to the block 23. 40

As it may be desirable on occasion to either 50 make or break the clock circuit manually, we provide the switch block 23 with a pin 72 which extends exteriorly of the casing and preferably projects through an arcuate slot 71 in the cover 50.

Fig. 6 shows a modification of our invention in which the temperature-controlled switch 2', instead of causing an interruption of current flow through the timing device upon breakdown of the lamp filament, operates a relay governing the supply circuit from which the current is obtained for lighting the lamp filament and driving said device. In the circuit connections described above the time register is driven by current 60 from the supply mains when its circuit is

closed. In this modification the register is located in the output circuit of the transformer and its movement is arrested by opening the input circuit of the transformer. The parts of the switch mechanism here illustrated are identical with those heretofore described and for the purpose of brevity, corresponding numerals, primed, are employed to indicate the corresponding parts. It will be noted in Fig. 6 that the block 23' is in an inverted position from that shown in Figs. 2 and 3. Thus, the thermal member 3' operates to open the cooperating contacts 10' and 21' when it starts to expand, and vice versa to close said contacts when it starts to contract. 70

A conductor 75 connects the conducting bar 19' to one output terminal of a double-pole switch 76 and a conductor 77 connects the supporting bar 6' to one end of the winding 78 of a relay 79, the other end of said winding 78 being connected by a conductor 80 to the other output terminal of the switch 76. The input terminals of the switch 76 are connected to the A. C. lighting source 83. The relay 79 has a movable armature 84 which normally engages a back contact 86 under the influence of spring 90. This pair of normally closed contacts 84 and 86 is connected in the circuit of the primary or low tension input winding 88 of the step-up transformer 89, the conductors 81, 87, 85 and 82 connecting said winding and pair of contacts in series and across said output terminals of the switch 76, so that, when the latter is closed, current normally flows through said winding 88. Upon energization of the relay winding 78 by a closure of the contacts 10' and 21', the relay armature 84 is attracted and the transformer input circuit interrupted. Provision is made for short circuiting the contacts 84 and 86 when desired, by the closing of a switch 92 the terminals of which are connected by conductors 93 and 94, respectively, to the conductors 85 and 87 leading to said contacts 84 and 86. 90

The secondary or high-tension output winding 95 of the transformer 89 is provided at one side portion with several taps 96 having terminals 97 which may take the form of suitable sockets into which terminal contacts 98, in the form of suitable plugs, may be inserted. The ends of the lamp filament, indicated by 101, terminate in the usual shell and center contacts and these are connected through the usual lamp socket (not shown) in circuit with the output of the transformer by conductors 99 and 100, the plug 98 to which one of said conductors is connected being inserted into the jack 97 100 providing the required voltage to be applied for testing purposes across the lamp 74. The clock 102 is connected through one of its terminals by a conductor 103 to the winding 95 and through its other terminal by a con- 110

ductor 104 to a separate plug 98, which is inserted into the jack 97 providing the required voltage for proper operation of said clock.

5 In preparation for a test with the circuit arrangement of Fig. 6, the switch 76 is closed and the switch 92 is also closed to permit current to flow from the source 83 through the low-tension winding of the 10 transformer 89 and consequently flow of current in the secondary circuits of said transformer to cause the filament of lamp 74 to become lighted and to start the register 102. Closing of the switch 92 is only necessary 15 momentarily to short circuit the relay contacts 84 and 86 to permit said lighting of the lamp filament and operation of the register, which would not take place, should the contacts 10' and 21' touch and the relay winding 78 be correspondingly energized upon 20 closing the switch 76. Instead of closing the switch 92, the block 23' may be operated manually, if desired, to break the contact at the switch 2', this preventing the relay winding 78 from being energized at the start of 25 the test.

The heat created when current flows through the lamp filament 101, causes the thermal strip 3' to press on the stop 25' and 30 tilt the block 23', which causes contact 21' to follow the movement of its cooperating contact 10'. The switch 92 remains open during the test. Upon the breaking down of the lamp filament 101, the expansion-strip 3' contracts, thereby almost immediately 35 thereafter closing the contacts 10' and 21' and establishing a circuit through the relay 78. This opens the contacts 84 and 86 and 40 interrupts the flow of current through the main supply, whereupon the mechanism of the clock 102 is arrested, the position of its hands indicating the life-period of the filament 101.

The embodiment of the invention shown 45 in Fig. 6 possesses the advantage that a number of lamps may be tested with the use of a single clock. A number of lamps may be connected in parallel with the lamp 74 or several lamps or groups of lamps may each 50 be connected by a suitable tap 96 of the transformer 89, each lamp being provided with a separate temperature-controlled switch 2' and separate relay 78, each of such relays controlling the flow of current 55 from the source 83 to the transformer 89. When a filament of any of the several lamps burns out, the register 102 is caused to stop and the current is interrupted through all of the filaments. A reading of the register 60 65 then gives the period of time over which the single disrupted filament extended. If desired this lamp may be replaced by a new one, or its thermal switch may be disconnected by merely moving the switch block to open its pair of contacts 10' and 21', and the

tests continued on the remaining filaments. A reading is taken from the register 102 each time a filament burns out, and by averaging the successive readings after breakdown of a plurality of filaments, the life-period of a 70 particular filament in normal service can be determined with considerable accuracy.

Fig. 7 shows a practical operative assembly of the parts. Here a lamp 105 is shown supported from a conventional socket 106 carried by the upper bracket portion 107 of a supporting frame 109. The housing 47 containing the temperature-controlled switch is properly positioned, relatively to the lamp, by securing said housing to another bracket 110 forming part of said frame. While this form of apparatus may be used for supporting a single lamp to be tested and heat-controlled switch therefor, it is understood that in practice life tests may be performed simultaneously on a large number of lamps. In such cases the lamps with their respective temperature-controlled switches may be mounted in successive rows on appropriate racks or like framework.

It is understood that the invention is not limited to the particular embodiments shown and described herein, and that other arrangements are possible without departing from its principle.

While we have described the invention in connection with incandescent lamps having filaments, it will be understood that specific reference to such lamps is for illustrative purposes only as indicative of a heat radiating body which in practice might be any article which when in use is subject to variants of temperature and the duration of which it may be desirable to measure. As a further example mention is made of the 105 gaseous type of lamp in which a luminous glow is obtained by the passage of current between electrodes within the bulb.

What we claim is:

1. In an apparatus for testing electric 110 lamps, the combination with a lamp, and means for supplying current to said lamp; of a temperature-controlled switch comprising an arcuate thermal expansion member disposed adjacent to said lamp, and circuit 115 contacts operated by said member to close under the effect of heat radiated from said lamp upon illumination and to open upon the termination of said illumination; a timing device, and electrical means controlled by said contacts for controlling the operation of the timing device.

2. In an apparatus for testing electric 120 lamps, the combination with a lamp, and means for supplying current therethrough; 125 of a temperature-controlled switch comprising an arcuate expansion member surrounding said lamp so as to be expanded by the heat radiated by the lamp when lighted and to contract when current through the lamp 130

is interrupted, and contact means operated by said member to close upon the movement of the latter in one direction and to open upon its movement in the other direction, 5 said contact means being movable as a whole to permit its operation substantially at the start of the expansion and the contraction of said member; a timing device, and electric means controlled by said switch for controlling 10 the operation of said timing device.

3. The combination with an electric lamp and means for supplying current thereto; of a temperature-controlled switch comprising an arcuate expansion-strip surrounding said 15 lamp and having a free end, a pivotal mounting, two spaced elements on said mounting adapted to be relatively fixed at opposite sides of said free end, said mounting being caused to pivot in either direction under the 20 influence of said expansion-strip, one of said elements cooperating as a contact with said strip and a housing for said parts; a timing device, and electrical means controlled by said cooperating contacts for controlling 25 the operation of said timing device.

4. The combination with an electric lamp and means for supplying current thereto; of a temperature-controlled switch comprising an expansion-strip surrounding said 30 lamp and expandable under the influence of radiated heat when current is caused to flow through said lamp and contractible when such current is interrupted, a contact carried by said strip, a pivoted member carrying two spaced stop elements located at opposite sides of said contact, one of said 35 stops operating as a circuit contact in co-operation with said expansion-strip contact, a ventilated housing for said parts, and 40 means for manually operating said pivoted member exteriorly of said housing; a timing device, and electrical means controlled by said cooperating contacts for controlling the 45 operation of said timing device.

45 5. In an apparatus for testing electric lamps, the combination with an electric lamp, and means for supplying current therethrough; of a temperature-controlled switch comprising an arcuate thermal-strip disposed around said lamp to permit it to expand under the influence of radiated heat when current is caused to flow through said lamp and to contract when such current is interrupted, and a pair of cooperating contacts adapted to alternately open and close upon expansion and contraction of said thermal-strip; a time indicating device, and means for supplying current to said device 55 through said switch.

6. In an apparatus for testing electric lamps, the combination with a lamp, and means for supplying current therethrough; of a temperature-controlled switch comprising a thermal expansion member disposed

adjacent said lamp, and circuit contacts operated by said member to close under the effect of heat radiated from said lamp upon illumination and to open upon the termination of said illumination; a relay in circuit with 70 said switch, and a timing device controlled by said relay.

7. In an apparatus for testing electric lamps, the combination with an electric lamp, and means for supplying current therethrough; of a temperature-controlled switch comprising an arcuate thermal-strip disposed around said lamp to permit it to contract from an expanded position when current through said lamp and heat radiated therefrom are interrupted, and contact means operated under the influence of said expansion-strip when contracting; and a timing device controlled by said contact means.

8. In an apparatus for testing electric lamps, the combination with a lamp and electrical means for supplying current through said lamp; of a temperature-controlled switch comprising an expansion-strip surrounding said lamp and adapted to contract from an expanded position when current through said lamp and heat radiated therefrom are interrupted, and contact means operated under the influence of said strip upon contracting, a timing device also operated by said electrical means, and a relay controlled by said switch and controlling said electrical means.

9. In a testing device for electric lamps, the combination with a lamp, a step-up transformer, an input circuit supplying current to said transformer, and an output circuit supplying current from said transformer to said lamp, of a timing device operated from one of said circuits, a thermostat actuated by heat from the lamp upon illumination and by interruption of said heat when the lamp filament burns out, and electrical means controlled by said thermostat for controlling the operation of said timing device.

10. In an apparatus for testing electric lamps, the combination with a lamp, of a timing device, means for supplying current to said lamp and to said timing device, a thermostat actuated by interruption of the heat radiated from said lamp upon cessation of current therethrough, and electrical means controlled by said thermostat for controlling said supply means.

11. In an apparatus for testing electric lamps, the combination with a lamp, and means for supplying current to said lamp, of a thermostat actuated by interruption of the heat radiated from said lamp upon cessation of current therethrough, a timing device, means for supplying current to said device, and means controlled by said thermostat for controlling said second supply means.

12. In an apparatus for testing electric lamps, the combination with a lamp, means including a step-up transformer for supplying voltage across said lamp, and means means controlled by said switch for controlling the operation of said timing device. In testimony whereof, we have signed this specification.
- PETER GARMS.
GEORGE LEWIS DIGGLES.
- 70
13. The combination with an electric lamp, and means for supplying current thereto; of a temperature-controlled switch comprising an arcuate expansion-strip surrounding said lamp and expansible under the influence of radiated heat when current is caused to flow through said lamp and contractible when such current is interrupted, a contact carried by said strip, a pivotal member carrying two spaced stop elements located at opposite sides of said contact, one of said stops operating as a circuit contact in cooperation with said expansion-strip contact, a housing for said parts, adjustable braking means cooperating with said member and mounted on said housing, and means for manually operating said member exteriorly of said housing; a timing device, and electrical means controlled by said cooperating contacts for controlling the operation of said timing device.
- 80
14. In an apparatus for testing electric lamps, the combination with a lamp, and means for supplying current to said lamp; of a temperature-controlled switch comprising a thermal expansion member disposed adjacent to said lamp so as to be expanded by the heat radiated by the lamp when lighted and to contract when current through the lamp is interrupted, and contact means operated by said member to close upon the movement of the latter in one direction and to open upon its movement in the other direction; a timing device, and electrical means controlled by said switch for controlling the operation of said timing device.
